Primary Examiner — Andrew Kerr*Assistant Examiner* — Chariton Alexakis(74) *Attorney, Agent, or Firm* — IPLA P.A.(57) **CLAIM**

The ornamental design for a disposable fork, as shown and described.

DESCRIPTION

FIG. 1 is a perspective view of my new design showing a disposable fork;

FIG. 2 is another perspective view of my new design showing a disposable fork;

FIG. 3 is a top plan view of FIG. 1;

FIG. 4 is a bottom plan view of FIG. 1;

FIG. 5 is a side elevation view of FIG. 1, the other side being a mirror image;

FIG. 6 is an enlarged elevation view of VI in FIG. 1;

FIG. 7 is an enlarged cross section taken along VII-VII in FIG. 3;

FIG. 8 is an enlarged cross section taken along VIII-VIII in FIG. 3; and,

FIG. 9 is an enlarged cross section taken along IX-IX in FIG. 3.

The short dash-long dash broken lines in FIGS. 1 and 6, designating the boundary of the enlarged view, form no part of the claimed design.

1 Claim, 5 Drawing Sheets(56)
